ANNEALING STAND CONSTRUCTION

William H. Dailey, Jr., Library, Pa., assignor to
Carnegie-Illinois Steel Corporation, a corpora-
tion of New Jersey

Application October 26, 1945, Serial No. 624,789

7 Claims. (Cl. 263—49)

1

The present invention relates to improvements in coil stands for annealing furnaces.

Prior to my invention, the conventional design of furnace base for the annealing of strip steel in coiled form usually comprised a rectangular structure fabricated of flat steel plates and structural shapes covered with refractory material. Normally, one to eight coil stands were superimposed on this flat steel base. The base was usually covered by one large inner cover or a number of individual inner covers in order to confine the annealing atmosphere required. Each coil stand consisted of a refractory pedestal, preferably of the insulating type, built up from the flat base and surmounted by a steel plate or cast open structure of heat-resisting metal upon which the coils to be annealed were placed. The purpose of the steel plate or metal structure was to provide a flat surface for maximum uniformity of load distribution to minimize the contact pressure at the lower edges of the steel coil.

As a result of demands for increased production, the piling height of coils on the coil stands has gradually been increased to a present maximum of about ten feet. This great increase in total load, together with impact loads due to placing of the upper coils, causes rapid failure of refractories in the coil stand. Stronger and more dense refractories have come into use in an attempt to solve the problem, but the strength was still found insufficient to withstand the loads imposed, and the insulating value is low.

One object of my invention is to overcome the inherent defects in prior art annealing coil stands.

Another object of the invention is to provide a coil stand where the coils to be annealed are supported entirely by metallic members of low heat conductivity extending from the base plate, located in a low temperature zone, through a body or a filling of insulating material to an intermediate bearing plate which carries the coil-supporting structures and is located in a high temperature zone.

A further object of the invention is to provide an annealing stand insulated to reduce heat losses to a minimum.

Another object is the reduction of operating delays through reduced maintenance requirements.

An additional object is to provide the structure and arrangement of parts as herein shown, described, and claimed.

For a more complete understanding of the invention, reference should be made to the following detailed disclosure, the accompanying drawings, and the appended claims.

2

In the drawings:

Figure 1 is a vertical longitudinal section through a portion of an annealing furnace equipped with the improved coil stand embodying the herein claimed invention.

Figure 2 is a plan view of the improved coil stand with the top plate and intermediate plates removed.

Figure 3 is a plan view of the intermediate 10 plate of the coil stand, showing the supporting ribs.

Figure 4 is a vertical section on line IV—IV of Figure 3.

Figure 5 is a view similar to Figure 1, showing a 15 preferred construction.

Figure 6 is a partial plan view of the stand of Figure 5.

Referring in detail to the drawings, reference numeral 10 represents any suitable masonry 20 foundation having a chamber 12 therein for giving access to the under side of the annealing furnace. Suitably supported on the foundation is a structural steel marginal frame formed of channel irons or similar rolled structural sections 14. Spanning the space between the members constituting the marginal frame 14 are a plurality of floor beams 16 to which are secured a steel or other metal floor 18. Spaced from the marginal frame members 14 and supported on the floor 18 are channel members 20, the space 30 between the outer members 14 and the members 20 being partially filled with a gas sealing medium such as sand, indicated at 22. An outer annealing furnace cover 24 is provided, and the lower portion 26 thereof enters the body of sealing sand 32. The outer cover includes a refractory lining 28 of conventional form and a bottom frame 30 which rests on the channels 20. Suitable heating means such as radiant tubes or other conventional form of heating device forming no part of the 40 present invention will usually be incorporated in the outer cover 24.

The herein claimed invention is directed to the construction and arrangement of parts constituting an improved type of coil stand indicated as a whole at 32 in Figures 1 and 5. The coil stand of Figures 1 to 4 includes a steel or other metal bottom plate 34, an outer annular steel shell 36 and an inner steel shell 38 concentric thereto and spaced inwardly therefrom by a ring 50 40 which spans the space between the shells, this ring being welded or otherwise secured thereto at its edges. A top ring 42 is welded or otherwise secured to the upper edge of the inner shell 38, as shown.

55 A multiplicity of uprights 44, which may take

the form of short lengths of pipe formed of metal of low heat conductivity, are arranged, for example, in four concentric rows, the lower ends of the pipes being preferably welded to the base plate 34. A filling of suitable insulating material 46 is provided so as to act as a barrier to prevent the escape of heat through the base of the apparatus. Instead of the pipes 44 I may use a series of rings as more fully described herein-after, in connection with Figures 5 and 6.

Loosely supported jointly by the top ring 42 and the upper extremities of the multiplicity of uprights 44 is a relatively heavy metal intermediate plate 48 having integrally formed thereon a multiplicity of upstanding radial ribs 50 jointly constituting a supporting grid for a relatively thick top plate 52 which loosely rests on the grid-like support. The top plate 52 forms a seat for the lowermost one of a plurality of coils 54 of steel strip, these coils constituting the charge of material to be annealed in the furnace. The coils may range in width from approximately 24 to 36 inches, and the total height of the stack of such superposed coils may be as much as ten feet. Such a stack of steel coils imposes a heavy static load on the apparatus, and the act of loading or stacking the coils from an overhead crane or the like imparts severe live loads to the supporting stand. The stand, having the detailed characteristics shown and claimed herein, is peculiarly well suited to bear the heavy loads involved and to resist the shocks and strains incident to charging the furnace.

The stack of coils to be annealed is enclosed by an inner cover 56 of conventional form whose lower end enters the space between the shells 36 and 38 and is embedded in a body of sealing sand 58, the lower end of the inner cover taking its bearing on the upper face of the metal ring 40. The base plate 34, the intermediate plate 48, and the top plate 52 are all substantially circular in plan as shown, and are provided with central apertures adapted to accommodate fan mechanism.

As shown by way of example in the drawings, there is a housing 60 having a flange 62 secured to the base plate 34. The housing 60 supports a fan driving mechanism indicated conventionally at 64. This mechanism may be regarded either as a direct drive motor or as an enclosure for a pulley driven by a suitable motor. The fan driving mechanism is adapted to rotate a fan impeller 66 located in the region of the central opening formed in the top plate 52 so as to induce circulation of gas through the space between the top plate 52 and the intermediate plate 48 and through the central void or opening 68 in the stack of superposed coils supported on the stand.

Suitable openings are provided in the base plate 34 and in the intermediate plate 48 for the passage of a pipe 70 adapted to be connected with a source of deoxidizing gas, this pipe having a laterally extending elbow or other fitting 72 for directing the deoxidizing gas inwardly or toward the fan 66. Suitable pipes, one of which is indicated at 74, are provided to facilitate the withdrawal of a sample of the gaseous atmosphere from the interior of the inner cover 56, for analytical purposes, and holes 76 may be provided for the introduction of thermocouples.

In the described structure, because of the non-rigid or loose association of the intermediate plate 48 with respect to the uprights 44 forming an integral part of the base, the parts are

free to move relatively to one another, under influence of expansion or contraction due to heat variations. Likewise, because the top plate 52 is loosely or non-rigidly associated with the supporting ribs 50, this part can also expand and contract freely. The described loose relationship of the parts thus greatly minimizes the strains heretofore induced in the structural assemblage, due to the drastic temperature fluctuations to which this character of apparatus is of necessity subjected.

In a preferred modification, as illustrated in Figures 5 and 6, instead of the pipe-like uprights 44 I use a plurality of substantially concentric corrugated rings 44^a, the corrugations of the rings endowing them with added strength. These rings, like the uprights 44 above referred to, are preferably made of metal of low heat conductivity such as stainless steel or nickel-chrome alloy. In this modification it is contemplated that instead of a loose filling of heat insulation, as in Figure 1, the body 46^a may be of a solid substance cast or molded around the several rings 44^a. Thus in this construction of Figures 5 and 6 the shells such as shown at 36 and 38 in Figure 1 will be omitted. The intermediate ring 40 and the top ring 42 will also be omitted, and in this modification the supporting members 44^a will extend upwardly beyond the top surface of the insulation body 46^a, and a plain flat plate 52^a may be loosely supported by the top edges of the several rings 44^a. The body of insulation 46^a may be formed with a suitable central aperture to accommodate a fan, but the fan may be omitted if desired. The lowermost coil to be heated in the pile may rest directly on the plate 52^a, and in this modification the bottom of the inner cover 56, instead of resting on the stand, may surround the stand and rest directly on the floor plate 18, as shown.

The bottom of the stand in the modification of Figure 5 will be a plain flat disc-like plate 34^a which will rest loosely on the floor plate 18. The several corrugated plates 44^a may be spot welded to the plate 34^a at spaced intervals, merely to facilitate assemblage of the parts. Spot or tack welding at widely spaced points is to be preferred to an integral union, so that there will be a low degree of heat transfer between the concentric rings 44^a and the base plate 34^a, an important characteristic of the stand being to provide good structural support for a pile or stack of coils, using metal members constructed of such material and so associated with the parts that there will be a minimum transfer of heat downwardly. Thus the upper part of the stand will be the hot zone and the lower part the relatively cooler zone.

In both embodiments of the invention illustrated, it is apparent that the static load of the pile of coils undergoing annealing treatment is transmitted through the uprights 44 or 44^a directly to the base plate 34 or 34^a, and in this manner the structurally weak filling or body of insulating material is not called upon to perform any load-supporting function.

When repairs are necessary, the stand can be removed as a unit by connecting overhead lifting tackle to fittings engaging openings in the base plate. In this manner the stand can be repaired whenever time is available. By the substitution or immediate installation of spare stands which will usually be kept on hand, the out-of-service or non-productive time of the furnace can be held down to a minimum. The

component parts of the described stand are all producible from stock materials capable of being handled and fabricated economically, and the assembled stand is of rugged construction especially well suited for withstanding operating conditions encountered in service.

Various modifications and substitutions of equivalents may be made by those skilled in the art without departure from the spirit and scope of the invention as defined in the appended claims.

I claim:

1. A stand of the character herein described, comprising a base plate adapted to rest on an annealing furnace floor, a multiplicity of uprights secured to said base plate, spaced marginal shells surrounding said uprights, an intermediate cover ring secured to and spanning the space between said spaced shells, a filling of heat insulating material confined about said uprights by said shells and said ring, and supporting means for coiled material to be annealed including upper and lower loosely associated plates spaced apart by ribs projecting from one of said plates, said supporting means being located directly above and transmitting its load by means of said uprights to said base plate.

2. A stand of the character herein described, comprising a base plate adapted to rest on an annealing furnace floor, a multiplicity of metal pipes welded at their lower ends to said base plate, spaced marginal shells surrounding said uprights, an intermediate cover ring secured to and spanning the space between said spaced shells, a filling of heat insulating material confined about said uprights by said shells and said ring, and supporting means for coiled material to be annealed including upper and lower loosely associated plates spaced apart by a plurality of radial ribs integral with and projecting upwardly from said bottom plate, said lower plate being supported on top of said uprights, said uprights being of sufficient number and strength to transfer the load of said coiled material to said base plate.

3. The stand defined in claim 1, wherein said shells and said base plate are substantially circular, the said bottom plate and the said supporting means all being centrally apertured, a fan adapted to induce circulation of gas from the space between said upper and lower plates and through the aperture in the center of said upper plate, fan driving means located below said base plate, and a housing secured to said base plate and supporting said fan driving means, part of said housing being accommodated in the apertured portions of said base plate and said lower plate.

4. A stand of the character herein described, comprising a metal base plate adapted to rest on an annealing furnace floor, a multiplicity of metallic uprights of low heat conductivity supported on top of and secured to said base plate, heat insulating material enclosing said uprights for the greater portions of their height, and means resting on top of said uprights for supporting

55
6 coiled material to be annealed, the said uprights being of sufficient number and strength to transfer the load of said coiled material to said base plate.

5. A stand of the character herein described, comprising a metal base plate adapted to rest on an annealing furnace floor, a multiplicity of corrugated rings formed of metal of low heat conductivity and supported on top of said base plate, a body of non-metallic heat insulating material supported on the base plate and in which said ring-like supports are embedded, and supporting means for coiled material to be annealed seated loosely on the upper extremities of the said rings, the said corrugated rings being of sufficient strength to transfer the load of said coiled material to said base plate.

15 6. A stand of the character herein described, comprising a base plate adapted to rest on an annealing furnace floor, a plurality of substantially concentric rings made of metal of low heat conductivity each secured to said base plate at spaced intervals, a body of non-metallic heat insulation resting on said base plate, said rings being embedded in said body of insulation, and supporting means for coiled material to be annealed including a plate resting on the upper extremities of said rings so as to relieve said body of insulation of the static load of the coils to be annealed, the said concentric rings being of sufficient strength to transfer the load of said coiled material to said base plate.

20 7. A stand of the character herein described, comprising a base plate adapted to rest on an annealing furnace floor, a multiplicity of uprights supported on top of and secured to said base plate, spaced marginal shells surrounding said uprights, an intermediate cover ring secured to and spanning the space between said spaced shells, a filling of heat insulating material confined about said uprights by said shells and said ring, and supporting means for coiled material to be annealed including upper and lower loosely associated plates spaced apart by ribs projecting upwardly from one of said plates, the said lower plate being supported on top of said uprights, the said uprights being of sufficient number and strength to transfer the load of said coiled material to said base plate.
